UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

DOOR-OPERATING MEANS.

1,185,511.

Specification of Letters Patent. Patented May 30, 1916.

Original application filed April 9, 1913, Serial No. 759,981. Divided and this application filed August 6, 1913. Serial No. 783,390.

To all whom it may concern:

Be it known that I, GEORGE B. KOHLER, a citizen of the United States, residing in Philadelphia, Pennsylvania, have invented 5 certain Improvements in Door-Operating Means, of which the following is a specification.

This invention relates to certain improvements in means for operating the doors of a 10 passenger car, or other vehicle, and is a division of an application for patent filed by me on the 9th day of April, 1913, under Serial No. 759,981, relating to door and step operating mechanism.

15 One object of the present invention is to provide simple and effective means for opening and closing pivoted doors.

A further object of this invention is to actuate the doors from a vertical shaft 20 through cams which can be adjusted on the shaft.

These objects I attain in the following manner, reference being had to the accompanying drawings, in which:

25 Figure 1 is a plan view partly in section on the line *a—a*, Fig 2; showing the platform of a passenger car partly broken away; Fig. 2 is a sectional elevation on the line *b—b*, Fig. 1 with the cams in side view; Fig.

30 3 is an enlarged sectional view illustrating the two cams and their rods; Fig. 4 is a plan view of one of the cams; and Fig. 5 is a detached perspective view illustrating the rod and its connection with the pivot of the 35 door.

Referring to the drawings, 1 is the body of a car.

2 is the platform, in the present instance, and 3, 4 are the doors located at one side 40 of the platform mounted on pivots 5 and 6 respectively. The doors are made in two parts and rods 7 are connected to the outer section of each door and to a fixed point 8 at the roof of the platform so that when the 45 doors are actuated the outer sections will be properly guided into the open or closed position, but the usual upper rail may be substituted for the bars without departing from the essential features of the invention.

50 9 is a vertically arranged operating shaft located at about the middle of the platform, in the present instance, and mounted in an upper bearing 10 which is attached to the rail 11 which extends over the platform, and

mounted in a lower bearing 12 located in the 55 floor 13 of the platform. Adjustably secured to the shaft by set screws and located under the floor are two cams 14 and 15 and at the upper end of the shaft is an operating handle 16. Each cam has a single slot 60 therein.

18, 18 are two rods. One rod extends over the upper cam and the other rod extends under the lower cam. The cams are arranged back to back. Both rods have slotted heads 65 19 and the shaft 9 extends through the slot in each head and acts as a guide for the inner ends of said rods.

Secured to the lower end of each pivot 5 and 6 is an arm 20. One rod 18 is secured 70 to one arm 20 and the other rod 18 is secured to the other arm 20. The head 19 has a pin 21 which extends into the groove in the upper cam 14 and the lower rod has a pin 22 which extends into the groove in the lower 75 cam so that when the operating shaft is turned the doors are opened or closed.

The cams are so formed, in the present instance, that when the doors are closed the pins are located in the concentric portion of 80 the groove of the cams and when the cams are turned in the direction of the arrow, Fig. 1, the door 3 will be opened first, followed by the other door 4. If the direction of movement of the shaft is reversed then the 85 door 4 will be opened first, followed by the door 3. This construction enables the operator to open either one of the doors, or both of them, with one operating handle.

By mounting the cams independently on 90 the shaft, I can locate the shaft at any point on the platform or I can pivot the doors at either edge and the cams can be set at the proper position after the shaft is locked.

The invention relates particularly to the 95 means for operating doors and the companion application hereinbefore referred to relates to the means for operating the steps located at one side of the platform below the doors.

As illustrated in Fig. 2, the step is pivoted at 23 and has a pin 24 which extends through a slot in an arm 25 on an extension of the pivots 5 and 6 of the doors so that as the doors are actuated the steps opposite to said 105 doors will be raised or lowered as the doors are closed or opened.

In the companion application, Serial No.

759,980, filed April 9, 1913, I have claimed broadly the means for operating the entrance and exit doors of a car and also, in this case, the construction in which a single ⁵ cam is used. The present case is limited to the construction of two cams, one for operating one door and the other for operating the other door.

I claim:

- 10 1. The combination of two vertically hung doors arranged side by side; a vertical operating shaft located some distance from the doors; two cams on said shaft; means for adjustably securing each of said cams to the shaft; and means controlled by the cams and connected to the doors, the cams being so shaped and arranged on the shaft that when the shaft is partly turned in one direction one door will be opened, followed by the ¹⁵ other door as the movement is continued, and, when the shaft is turned in the opposite direction, the last mentioned door will be opened and the first mentioned door will follow.
- 20

Copies of this patent may be obtained for five cents each, by addressing the "Commissioner of Patents, Washington, D. C."

2. The combination of a floor; two doors ²⁵ located above the floor; a pivot for each of said doors extending under the floor; an arm on each pivot below the floor; a vertical operating shaft extending through the floor; two cams on the operating shaft arranged ³⁰ back to back, both cams being located under the floor; two rods having slotted heads through which the operating shaft extends and by which they are guided; a pin on each slotted head arranged to enter a slot in one ³⁵ of the cams, one rod being connected to an arm on the pivot of one door and the other rod being connected to an arm on the pivot of the other door so that, on turning the shaft, the doors will be opened or closed. ⁴⁰

In testimony whereof I have signed my name to this specification in the presence of two subscribing witnesses.

GEORGE B. KOHLER.
